(57) **CLAIM**

The ornamental design for a pet seat cover, as shown and described.

DESCRIPTION

FIG. 1 is a first perspective view of a pet seat cover showing our new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines and de-emphasized half tone portions illustrate portions of the pet seat cover that form no part of the claim design.

1 Claim, 8 Drawing Sheets(56)
